UNITED STATES PATENT OFFICE.

JOHN ARTHUR CHILSTROM, OF WINTHROP, MINNESOTA.

CABINET FOR LACES, TRIMMINGS, &c.

No. 893,983.

Specification of Letters Patent.

Patented July 21, 1908.

Application filed May 22, 1907. Serial No. 375,156.

To all whom it may concern:

Be it known that I, JOHN ARTHUR CHILSTROM, of Winthrop, in the county of Sibley and State of Minnesota, have invented certain new and useful Improvements in Cabinets for Laces, Trimmings, &c.; and I do hereby declare the following to be a full, clear, and exact description of the invention, such as will enable others skilled in the art to which it appertains to make and use the same.

My invention relates to improvements in cabinets for laces, trimmings or embroideries, the object of the invention being to so construct such a cabinet that it shall be sectional and adapted to contain all sizes of stock.

A further object is to provide a cabinet of the character above stated in which the stock can be arranged in regular order; so that it can be readily adapted for stock of various sizes and so that the goods can be readily placed therein and easily removed therefrom.

25 A further object is to produce a cabinet for laces, &c., which shall be simple in construction, cheap to manufacture, and neat in appearance.

With these objects in view the invention 30 consists in certain novel features of construction and combinations of parts as hereinafter set forth and pointed out in the claims.

In the accompanying drawings Figure 1 35 is a perspective view of a cabinet showing an embodiment of my improvements; Fig. 2 is a longitudinal sectional view through two sections of the cabinet; Fig. 3 is a transverse sectional view through one drawer; Figs. 4 and 5 are fragmentary views illustrating the guideways 5 and 7; Fig. 6 is a perspective view of one of the cores or tins on which the goods is wound, and Fig. 7 is a sectional view of said core or tin.

45 1 represents a cabinet, comprising several sections 2, placed one upon another and each containing a drawer 3 which can be withdrawn from either side of the cabinet, and each end of each drawer is provided 50 with a glass panel 4, through which the goods can be viewed. Each drawer is provided interiorly along its respective sides with a number of guide-ways 5 for the reception of the cores or tins (hereinafter described) on

which the goods is wound. These guide-ways 5 may be conveniently made by means of saw kerfs in the lower thickened portions of the sides of the drawer. Each drawer may be divided into any desired number of compartments by means of longitudinally disposed movable partitions 6, and each partition may be conveniently made of wood and provided in each face with a series of transverse saw-kerfs, which when the partition is in place will be disposed vertically 65 and constitute guide-ways 7 to align with the guide-ways 5 in the side of the drawer or with similar guide-ways 7 in another partition. Thus a drawer may be arranged to contain a single row of laces or it may be divided by means of the partitions to contain two, three or four rows. The drawers may be made of any desired length, but I prefer to make them of such size that they will accommodate about twenty-three pieces of 70 goods in a row.

The cores 8 on which the goods are wound are preferably made of sheet metal, such as tin, and readily enter the saw-kerf guide-ways in the sides of the drawer and the partitions. Each core or tin is provided at its respective ends with depending lugs 9 which rest upon the bottom of the drawer, and between these lugs, the metal of the core is turned upon itself as shown at 9^a to protect 85 the lace wound on the core. The upper edge of the core is provided at each end thereof, with integral extensions which are bent into triangular form and constitute 90 holders 10 for cards 12 of celluloid or other material, and these cards are held in place by means of clips or covers 13 having holes 14 through which data on said cards can be viewed. On one of the cards 12 the price 95 of the goods may be written and the other card may have written or printed thereon, the number of the piece of goods on the core. These numbers will be made to correspond 100 with those in a sample book so that a clerk in making a sale to a purchaser from the sample book, can readily and quickly locate the piece desired in the cabinet.

The metal of the core between the holders 10 is bent upon itself as shown at 15 to protect the tap on the core.

Slight changes might be made in the details of construction of my invention and also in the kind of material which may be

employed without departing from the spirit of the invention or limiting its scope, and hence I do not wish to restrict myself to the precise details of construction nor to any particular kind of material.

Having fully described my invention what I claim as new and desire to secure by Letters-Patent, is—

1. Means for holding laces and the like, comprising a core piece provided with a label holder forming a permanent part thereof, said label holder disposed above the upper edge of the core piece and at an angle to the side faces thereof, and means for supporting the core piece in position to expose the label holder.

2. Means for holding laces and the like, comprising a flat core piece provided with two label holders to receive labels containing data indicating the price of the goods and the number of the piece of goods on the core, said label holders being disposed parallel with the upper edge of the core and at right angles to the sides of the core, and means

for supporting said core in position to expose 25 both labels.

3. Means for holding laces and the like, comprising a sheet metal core piece, having the metal bent upon itself at its upper and lower edges, and having portions projecting 30 above and below the top and bottom edges respectively, at the ends of the core piece.

4. Means for holding laces and the like, comprising a flat core piece, fixed label holders projecting above the upper edge of 35 the core piece at respective ends thereof, said label holders being disposed parallel with said upper edge of the core and at right angles to the sides of the latter, and lugs projecting downwardly from the lower edge of 40 the core piece at respective ends thereof.

In testimony whereof, I have signed this specification in the presence of two subscribing witnesses.

JOHN ARTHUR CHILSTROM.
